United States Patent Office

Des. 191,805

Patented Nov. 21, 1961

191,805

COATED PAPER

Howard L. Amberson, Madison, Wis., assignor to United States Rubber Company, New York, N.Y., a corporation of New Jersey

Filed June 16, 1961, Ser. No. 65,623

Term of patent 14 years

(Cl. D59—2)

The figure is a plan view of a coated paper showing my new design. A repeat unit is enclosed within the dash and dot lines.

I claim:

The ornamental design for a coated paper, as shown and described.
